UNITED STATES PATENT OFFICE

148,264

DESIGN FOR A NUTCRACKER OR SIMILAR ARTICLE

Alfred Welker, Detroit, Mich.

Application March 12, 1946, Serial No. 127,392

Term of patent 3½ years

(Cl. D44—1)

To all whom it may concern:

Be it known that I, Alfred Welker, a citizen of the United States, residing at Detroit, in the county of Wayne and State of Michigan, have invented a new, original, and ornamental Design for a Nutcracker or Similar Article, of which the following is a specification, reference being had to the accompanying drawing, forming part thereof.

Figure 1 is a side elevational view of a nut cracker or similar article, showing my new design, Figure 2 is a top plan view, and

Figure 3 is a front elevational view thereof.

The essential features of my design reside in the specific configuration and ornamentation of the base member of the nut cracker.

I claim:

The ornamental design for a nutcracker or similar article, as shown and described.

ALFRED WELKER.
